COMBINED CANDLE AND HOLDER THEREFOR

Charles S. Justus, Oakland, Calif.

Application April 19, 1954, Serial No. 30,071

Term of patent 14 years

(Cl. D73—1)

To all whom it may concern:

Be it known that I, Charles S. Justus, a citizen of the United States and a resident of Oakland, county of Alameda and State of California, have invented a new, original, and ornamental Design for a Combined Candle and Holder Therefor, of which the following is a specification, reference being had to the accompanying drawing, forming a part hereof.

I claim:

The ornamental design for a combined candle and holder therefor, as shown.
